Primary Examiner—Ted Shooman**Assistant Examiner**—Mitchell I. Siegel**Attorney, Agent, or Firm**—Kelly Bauersfeld Lowry & Kelley, LLP**[57] CLAIM**

The ornamental design for a iron-type head for a golf club, as shown.

DESCRIPTION

FIG. 1 is a perspective view showing the rear and right sides of an iron-type head for a golf club embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a sectional view taken on the line 8—8 of FIG. 3; FIG. 9 is an enlarged sectional view taken on the line 9—9 of FIG. 3;

FIG. 10 is a perspective view showing the rear and right sides of a second embodiment of my new design, the front, right and left side elevational views and the top and bottom plan views being identical to the embodiment of FIGS. 1-7; FIG. 11 is a rear elevational view of the embodiment of FIG. 10;

FIG. 12 is a sectional view taken on the line 12—12 of FIG. 11; and,

FIG. 13 is an enlarged sectional view taken on the line 13—13 of FIG. 11.
